UNITED STATES PATENT OFFICE.

JAMES N. CROFUT, OF BROOKLYN, NEW YORK, ASSIGNOR TO MERGENTHALER LINOTYPE COMPANY, A CORPORATION OF NEW YORK.

TYPE-BAR.

1,117,797.

Specification of Letters Patent. Patented Nov. 17, 1914.

Application filed October 7, 1912. Serial No. 724,266.

To all whom it may concern:

Be it known that I, JAMES N. CROFUT, a citizen of the United States, and a resident of Brooklyn, county of Kings, and State of New York, have invented a new and useful Improvement in Type-Bars, of which the following is a specification.

My invention relates to type bars, such for instance as linotypes, familiar to those skilled in the art. These bars ordinarily comprise a body portion which carries and supports the printing characters or type on one edge thereof. In use, they are assembled side by side and locked in a form, which may be then employed for direct printing, or for stereotyping, etc. These bars are formed in different ways, but principally by casting, as in the case of the linotype. For instance, the latter is ordinarily formed in a mold, comprising a main or body portion, a cap, and end liners removably secured therebetween, such as is disclosed in United States Letters Patent to G. A. Bates, No. 618,554. It sometimes happens, and particularly when the parts have been used to a considerable extent, that the joints between the liners and the body and cap portions are not tight, and as a result thereof, that fins or sprues are formed in the casting. Such fins or sprues quite frequently project beyond the effective or operative surfaces of the slug, and in such a manner as to interfere with the proper locking of the form. To obviate this difficulty is the principal object of my invention, and to that end I form the body portion of the linotype or slug with a recess in its corner edge, adapted to receive and contain this accidental fin or sprue, and thus to prevent its projection beyond the operative or effective surfaces thereof.

In the accompanying drawing, I have shown my invention in preferred form and by way of example, and as applied to a linotype slug, but obviously many variations and modifications may be made therein, and in its mode of application, without departure from its spirit. Generally speaking, I desire it to be understood that I do not limit myself to any specific form or embodiment, except in so far as such limitations are specified in the claims.

Referring to the drawing; Figure 1 is an end view of a number of slugs or linotypes assembled side by side; Fig. 2 is a perspec-

tive view of two such slugs; and Fig. 3 is an end view of a slug, illustrating the function and advantages of my invention.

Referring to the drawing, the slugs A consist of the body portion D, having substantially the same thickness as the slug itself, and the type or printing characters B mounted on an edge thereof. When the slugs are to be employed for printing or stereotyping, they are assembled side by side and then locked in a form, locking or holding pressure for this purpose being brought to bear upon the ends C of the slugs. If there be fins or sprues projecting beyond such ends, it is obvious that the locking operation will be seriously interfered with. To obviate this difficulty, I form the corner edges of the body D of the slug with recesses E, in the form specifically shown, these recesses terminating at a point just below the upper longitudinal edge of the slug. Due to this construction, it will be apparent, if the mold joint be not tight, that the fin or sprue formed thereby will be received and contained within the recess, and that thus it will be prevented from projecting beyond the effective end of the slug. This is clearly shown in Fig. 3, where a fin or sprue F is indicated within the recess E and terminating short of the end C of the slug. I may similarly form a recess G along the lower corner edge of the slug, with the same effect.

My improved slugs, recessed along the corner edges of the body portion in the manner and for the purposes described, are to be distinguished from slugs having a body portion and alining ribs projecting from the side of such portion, as the apparent recess thus formed by a rib does not and cannot subserve my function, which is secured only when the recess is formed directly in the body portion.

As previously stated, many modifications and variations of my invention, and its mode of application, will suggest themselves to those skilled in the art and still be comprised within its scope.

Having thus described my invention, its construction and mode of operation, what I claim and desire to secure by Letters Patent of the United States is as follows:

1. A slug comprising a body portion formed in its side face at its corner edge with a recess, the said recess extending only

partially through the body portion and located within the effective length thereof, for the purpose described.

2. A slug comprising a body portion of substantially the same thickness as the slug itself, the said body portion being formed in its side face at its corner edge with a recess extending only partially through the body portion and located within its effective length, for the purpose described.

3. A slug of substantially uniform thickness throughout its length and formed in its side face at its corner edge with a recess, the said recess extending only partially through the slug and located within its effective length, for the purpose described.

4. A slug comprising a body portion of uniform thickness, the said body portion

being formed in its side face at its corner edge with a recess located within its effective length, the said recess extending only partially through the body portion and from a point below the upper longitudinal edge of the slug, for the purpose described.

5. A slug comprising a body portion cut away at its corner edge in its side face, said cut extending only partially through the body portion and located within its effective length, for the purpose described.

In testimony whereof I hereunto set my hand this third day of October, 1912, in the presence of two attesting witnesses.

JAMES N. CROFUT.
